UNITED STATES PATENT OFFICE.

WILLIAM THEODORE DITCHAM, OF TWICKENHAM, ENGLAND.

TRANSMITTER FOR WIRELESS TELEPHONY.

1,083,686.

Specification of Letters Patent.

Patented Mar. 3, 1914.

Application filed April 9, 1913. Serial No. 759,897.

To all whom it may concern:

Be it known that I, WILLIAM THEODORE DITCHAM, a subject of the King of Great Britain, residing at 4^a Lebanon Park Mansions, Twickenham, in the county of Middlesex, England, have invented new and useful Improvements in Transmitters for Wireless Telephony, of which the following is a specification.

10 For wireless telephony this invention relates to improved means for producing electro-magnetic wave-trains of a group-frequency exceeding the limits of audibility and superimposing thereon a voice-characterization. To generate the required rapid succession of sparks by the energy of direct-current electricity, I make use of the known arrangement of leading the electric energy to and from a spark-gap through inductive 20 resistances, a shunt-circuit containing a condenser and an inductance being provided therewith. To prevent the failure of the operation by the production of a continuous arc in substitution for a succession of sparks, 25 I take advantage of the known devices of greatly promoting the cooling of the electrodes by forming them of relatively large mass adapted to conduct heat rapidly away from their sparking extremities, mounting 30 them so that they may be rotated with facility and thereby present successive sparking points, employing an air blast, surrounding them with an atmosphere consisting of or comprising hydrogen, or immersing them 35 in an insulating liquid. On these means for preventing arcing is superposed a tight-coupling between the inductance of the energized shunt-circuit and the inductance of the radiating air-wire, which tight-coupling 40 has, in wireless telegraphy, previously been proposed, in conjunction with good radiating properties of the antenna, to absorb completely the energy of the primary circuit and radiate it into the surrounding medium. 45 Such transfer of energy from the spark-gap will still further augment the possible frequency of sparking without arcing. In addition preferably advantage is taken of the known device of employing two short rods 50 of dissimilar metals for the electrodes of the spark gap such as, for example, copper and silver or copper and aluminium, the faces of the rods being parallel and closely adjacent and connected to masses of heat- 55 conducting metal. In order to perform the

double function of tight-coupling the inductance of the energized shunt-circuit with the inductance of the radiating air-wire and superposing on the soundless electro-magnetic waves, which are transmitted from the 60 radiating air-wire, a voice characterization, there is interposed a circuit which is conductively continuous through a microphone or equivalent thereof, that is, a circuit which does not contain a condenser and therefore 65 does not possess a definite frequency of oscillation the said interposed microphone circuit having an inductance which is tightly-coupled to the inductance of the energized shunt-circuit and another inductance which 70 is tightly coupled to that of the radiating air-wire. The inductances above mentioned are preferably so arranged that the inductance of the shunt-circuit cannot directly affect the inductance of the radiating air-wire to any appreciable degree, the latter being influenced by the former only through 75 the medium of the interposed microphone circuit. In effecting the said tight-coupling through the medium of the said interposed microphone circuit, one of the inductances of the latter may serve also for the inductance of the shunt-circuit or for the inductance of the radiating air-wire.

In place of an elevated air-wire the wave 80 trains may be radiated from a long horizontal insulated wire laid on or below the ground or suspended a short distance above the ground, and inductively or galvanically connected at its center part to the condenser 85 shunt-circuit, and the said horizontal wire may have its ends left free or its ends 90 may be connected to the earth through condensers.

On the accompanying drawing are shown 95 diagrammatically, three different arrangements of the above mentioned elements in the described interposed microphone circuit. In each of the three figures the circuit which is energized by the direct-current supply is 100 the same and is similarly lettered, L¹ L² being the direct-current supply leads, I³ I⁴ choking coils contained therein. R is a resistance. S is the spark-gap, indicated as a 105 cooled spark-gap, and C is a condenser and I² an inductance contained in the shunt-circuit. The radiating air-wire is indicated by A, I¹ being the inductance contained therein and E the earth or counter-capacity.

In Figure 1 the interposed microphone 110

circuit comprises an inductance I^6 tightly-coupled with the inductance I^2 of the shunt-circuit and another inductance I^6 tightly-coupled with the inductance I^1 of the radiating air-wire, the inductance I^1 being so situated relatively to the inductance I^2 as for example by placing the axes of the coils at right-angles to one another, that the inductance I^2 cannot directly affect the inductance I^1 . In Fig. 2 the arrangement is varied by causing the inductance I^1 in the radiating air-wire to serve also the purpose of the before-mentioned inductance I^6 in Fig. 1. By such a modified construction the inductance 15 of the interposed circuit will be virtually coupled to the inductance of the radiating air-wire with the maximum degree of tightness as far as the dimensions of the inductance I^1 will allow. Similarly in Fig. 3 the before-mentioned inductance I^2 is made to serve, in addition, the function of the before-mentioned inductance I^6 so that these inductances may be regarded as being coupled with the maximum degree of tightness.

I claim:—

In a transmitter for wireless telephony, a source of direct current electricity, inductances in the circuit thereof, a high frequency quenched spark circuit connected to said direct current circuit between said inductances and comprising a rapidly quenched spark gap in series with said direct circuit and a condenser and an inductance in parallel with said spark gap, a radiating air wire, an inductance in said air wire inductively separated from said spark circuit inductance, a continuous circuit tightly coupled to said spark circuit inductance and to said air wire inductance and a microphone in said continuous circuit.

In testimony whereof I have signed my name to this specification in the presence of two subscribing witnesses.

WILLIAM THEODORE DITCHAM.
